COMBINED SKI AND SKI POLE RACK

Robert J. Borraccio, 7720 Stenton Ave.,
Philadelphia, Pa. 19118

Filed June 21, 1972, Ser. No. 264,709

Term of patent 14 years

Int. Cl. D6—06

U.S. Cl. D6—114

FIG. 3

FIG. 1 is a front elevation view of the combined ski and ski pole rack;

FIG. 2 is a top plan view thereof; and

FIG. 3 is a sectional view thereof taken along the lines 3—3 of FIG. 1.

I claim:

The ornamental design for a combined ski and ski pole rack, as shown.
